UNITED STATES PATENT OFFICE.

BENJAMIN W. KLEIN, OF MOUNT VERNON, NEW YORK.

DESIGN FOR A CUSTOMER'S WAITING BOOTH.

Application filed October 16, 1922. Serial No. 3,992. Term of patent 3½ years.

To all whom it may concern:

Be it known that I, BENJAMIN W. KLEIN, a citizen of the United States, and a resident of Mount Vernon, county of Westchester, and State of New York, have invented a certain new, original, and ornamental Design for Customer's Waiting Booth, of which the following is a specification, reference being had to the accompanying drawing, forming part thereof.

In the drawing

I claim:

The ornamental design for a customer's waiting booth, as shown.

BENJAMIN W. KLEIN.
